Des. 1298

Walter W. Standard, of Buffalo, N.Y.
Assignor to
Sherman J. Jewett & Francis B. Root, of same place.
Letters Patent No. 1298 Dated July 3d, 1860.

The schedule referred to in these Letters Patent and making part of the same.

To all whom it may concern:

Be it known that I, Walter W. Standard, of the City of Buffalo,
County of Erie, and State of New York, have invented or produced a certain new and
original ornamental Design, for Cooking Stoves, and I do hereby desire that the
following is a full, clear, and exact description of the same, reference being had to
the accompanying photographic drawings, and the letters of reference marked thereon.

Fig: I, Represents the front plate of the stove, It has two sets of sli-

ding doors, a. & b. The doors, a, are surrounded by a quarter, concave, ogee, and half round moulding, c. A short distance below the centre of each panel, is an ogee bow, d, with concave denticulations at its base. It is surrounded by reversed scroll mouldings, d', e, at the sides and bottom, and leaf and ornaments, f, at the top.

The panels of the jambs on either side of the sliding doors, have an ornament of reversed embossed scrolls, g, at the centre, with an embossed crown, h, and urn, i, at the top and bottom.

Above the sliding doors, a, the surface of the plate is ogee in form, and the sliding doors, b, are made to correspond. These doors are surrounded by a plain quarter round moulding, j, and half round bead moulding, k, and their panels are ornamented by a similar ornament to that of the doors, a. On either side of the doors, b, is a sunken reticulated panel, l, with a scroll border.

Fig: II. Represents one of the side plates of the stove. It has a fluted panel, m, arched at the top as represented. Over this panel, m, is a small diamond shaped panel, n, with vertical flues.

o, is a long narrow, horizontal panel ornamented by three sed shells, p, (commonly called periwinkles), scroll mouldings, q, and leaves, r, as represented in the drawing. The opposite side plate is similar in all respects to the one just described.

Fig: III. Represents one of the end plates of the stove. It is surrounded by a plain, concave, and quarter round moulding, s.

t, is the door of the fire chamber. Its upper corners are rounded, and it is surrounded, by an ogee and quarter round moulding, u. It has a central ornamental panel, v, with diamond shaped reticulations, which is surrounded by a border of curved moulding, w, with embossed ornaments, x, at the top and bottom, and terminating at the sides in circular beads, and points, y. Between the central panel and the moulding surrounding the door is a border of reversed spear heads, z, at the sides and at the top and bottom, with carved or embossed scrolls, 'z', at the corners. The opposite end plate is the same in all respects, except that the door, t, is a stationary panel.

Fig: IV. Represents one of the side plates of the oven. It is surrounded by a concave and quarter round moulding, a', the same as that surrounding the end plate Fig: III.

The plate has a central ornamental panel, b', of a similar

Dec. 1298

design to the panel, v, described in Fig. 111, but reversed with reference to the upper edge of the plate. A large water ring is formed around this central panel, by the curved, half round and bead moulding, c', which terminate at the ends and at the top and bottom and near the ends in the curved scrolls, d', with spear points, e', and ornaments, f', between them.

I claim the ornamental design for Cooking Stoves herein described.

Witnesses.
Walter H. Gorham.
E. M. Davis.
